UNITED STATES PATENT OFFICE.

JACOB H. REIGHARD AND C. L. KNECHT, OF BIRMINGHAM, PENNSYLVANIA.

ATTACHMENT FOR HINGED COVERS OF GLASS VESSELS.

Specification of Letters Patent No. 29,718, dated August 21, 1860.

To all whom it may concern:

Be it known that we, JACOB H. REIGHARD and C. LOUIS KNECHT, residing at Birmingham, in the county of Allegheny and State 5 of Pennsylvania, have invented a new and useful Improvement in the Mode of Fastening Metallic Caps to Glass Mugs, &c.; and we do hereby declare the following to be a full, clear, and exact description thereof, 10 reference being had to the annexed drawing, forming part of this specification, in which—

Figure 1, is a perspective view of a mug with a metallic cover attached on an improved plan. Fig. 2 is a vertical section 15 through the handle of a glass mug at the point where the metallic cap is attached thereto.

It is a usual thing to furnish certain articles made of glass ware, such as lager 20 beer mugs, cream pitchers &c, with a cap or covering of metal, which closes down on to the glass edge or mouth of the vessel, and which is hinged, so as to open and shut, and is attached to the glass by fastening the 25 lower part of the hinge to the top of the handle of the vessel. The mode of securing the hinge of the cap to the glass handle, has been heretofore to cast the lower hinge piece around the glass handle by forming the 30 mold or matrix in which the hinge is cast around the glass handle, and casting the lower hinge piece so as to form a strap or belt around the handle. The effect of this is, notwithstanding the greatest care is exer- 35 cised, that the heat of the metal, cracks the glass, so that there is great loss in this mode of attaching the metallic coverings. By our improved method, however, all danger of 40 breaking the glass is obviated, and the covers may be very easily and rapidly attached to the glass.

To enable others skilled in the art to make use of our improvement, we will proceed to describe the mode of carrying it 45 into practice.

The drawings represent our improvement as applied to a lager beer mug. The mug *a* is made of glass, being pressed in a mold in the usual way. The handle as well as the 50 body of the mug is pressed, which is effected in the manner well known in the art, by means of a mold dividing vertically through the handle. On top of the handle, near to

the body of the mug, is a flat surface to serve as a seat for the lower part *b* of the hinge of the cover *c*. In pressing the glass mug, a hole is made in the handle, which passes vertically through the handle, at or near the middle of the hinge seat. This hole (which is at *d* Fig. 2) is somewhat enlarged at the lower end, so as to prevent the hinge from pulling out. This hole in the handle is readily made by inserting a pin at the proper place in the mold in which the mug is pressed. The cap or cover *c* is made 65 to suit the fancy and the size and shape of the article to which it is to be attached. At one point in its circumference is a hinge composed as usual of two pieces, one *e* attached to the cover *c*, and inserted into suitable 70 spaces in the lower piece *b*, the two pieces being united by a hinge pin. The under side of the lower hinge piece *b* is made flat and smooth, so as to set on its seat on the top of the glass handle, and a metallic 75 pin *f* of the size of the hole in the glass handle, projects downward from the lower hinge-piece *b* in the proper position. By this pin *f* the hinge is secured to the glass 80 handle. The pin is passed through the hole in the handle, and being a little longer than the depth of the hole, it projects through. The pin which is made of soft white metal (as the cap and hinge are usually) is then 85 touched at its projecting point, with a hot iron, which melts it, and causes the metal to run into the hole, which being slightly enlarged at its bottom forms a head at the end of the pin, and prevents its being drawn out of its place. As the pin is melted only 90 at its extremity, the heat is not sufficient to crack the glass, and the operation of putting on the covers may be performed very rapidly.

As the caps or covers, and the lower hinge piece, with its pin, are usually cast in a 95 mold, and the glass mug is also pressed in a mold, the parts are made so as to fit exactly, without any adjustment.

This mode of attaching covers to glass vessels, is applicable to cream pitchers and 100 various other articles of glass which may be made in molds.

Having thus described our improvements, what we claim as our invention, and desire to secure by Letters Patent, is—

105 Attaching caps or covers to mugs and

other articles of glass ware, by means of a hole pressed through the glass handle, of the vessel through which is passed a metallic pin attached to or forming part of the hinge of the cover constructed and secured in the manner described.

In testimony whereof we, the said JACOB

H. REIGHARD and C. LOUIS KNECHT, have hereunto set our hands.

JACOB H. REIGHARD.
C. L. KNECHT.
